UNITED STATES PATENT OFFICE.

GEORGE WESTINGHOUSE, JR., OF PITTSBURG, PENNSYLVANIA.

SYSTEM FOR THE PROTECTION OF RAILROAD-TRACKS AND GAS-PIPE LINES.

SPECIFICATION forming part of Letters Patent No. 314,089, dated March 17, 1885.

Application filed August 21, 1884. (No model.)

To all whom it may concern:

Be it known that I, GEORGE WESTINGHOUSE, Jr., a citizen of the United States, residing at Pittsburg, in the county of Allegheny 5 and State of Pennsylvania, have invented or discovered a certain new and useful Improvement in Systems for the Protection of Railroad-Tracks and Gas-Pipe Lines, of which improvement the following is a specification.

10 In the accompanying drawings, which make part of this specification, the figure is a transverse section through the road-bed and super-structure of a railroad, and a longitudinal section through a portion of a gas-pipe line, illustrating the application of my invention.

15 The object of my invention is to obviate liability to accident from the leakage of inflammable or explosive gas from a pipe-line at or near the tracks of a railroad; to which end my 20 invention consists in the combination, with a gas-main, of a tight casing inclosing said main adjacent to a railroad-track, a connecting-pipe admitting gas at low pressure from the main to the interior of said casing, an escape-pipe 25 fitted with a relief-valve and leading out of said casing, and a gas-burner inclosed in a lantern located in position to be seen from the railroad-track, and communicating by a supply-pipe with said casing. The improvement 30 claimed is hereinafter fully set forth.

35 The operation of pipe-lines which convey natural gas or other high-pressure gas of an inflammable or explosive character across the line of or adjacent to a railroad-track is at- tended with danger from the liability to undetected leakage of gas from the main and its 40 ignition by sparks from passing engines, involving the risk of an explosion, causing loss of life and property, and it becomes specially important and desirable to interpose the most 45 efficient safeguards against such disaster. The application of my invention enables this result to be readily and inexpensively effected without in any wise interfering with the usual and normal operation of either line.

50 In the practice of my invention I inclose the gas-main 1 at the crossing of the line of railroad 2, and for a safe distance—say one hundred feet or more on each side thereof—within

closed at each end and forms, with the main 1, an annular chamber, 4, which is designed to be continuously charged with gas at a low pressure, the supply thereof being afforded by a connecting-pipe, 5, leading from the main 55 1 to the chamber 4, and regulated either by a valve, 6, in the connecting-pipe, or by making the pipe of such small diameter as to reduce the supply-pressure to the desired degree. An escape-pipe, 7, one or more, the 60 area of which is sufficient to admit of the passage of any excess of gas beyond the capacity of safe resistance of the low-pressure chamber 4, is connected thereto at any convenient point in its length, and is fitted at its outer end with 65 a relief-valve, 8, loaded in correspondence with and not to exceed the maximum pressure which can be safely sustained by the low-pressure chamber, but preferably to discharge 70 gas at low pressure. The discharge-opening 70 of the escape-pipe 7 is located at such distance above or laterally from the line of railroad as to be exempt from any liability to ignition of the escaping gas from fire that may be thrown from engines passing on the line. A lantern, 75 9, is supported in such position as to be in full and plain view of the train and track men of the railroad, and a gas-burner, 10, inclosed within the lantern 9, so as to be protected from drafts of air, receives a constant supply of gas 80 by a pipe, 11, from the chamber 4.

In operation any increase of pressure in the chamber 4 resultant upon leakage from the main 1 will be shown by an increased flame at the burner 10, which, being observed 85 by engineers or track-inspectors, can be forthwith reported to those in charge of the pipe-line, so that the leak may be located and stopped without delay. The extent of the leakage will be indicated by the character of 90 the flame, and in the event of its becoming in excess of the capacity of the chamber 4, pending repairs to the pipe-line, it will be relieved without danger by the valve 8 of the escape-pipe 7.

95 While I have herein illustrated my improvements as applied at the crossing of a line of railroad, it will be obvious that they are similarly applicable when a pipe-line adjoins without crossing a railroad-track, as in the nature 100

of a tangent to a curve thereon or parallel thereto in rock-cutting or other narrow passages.

I disclaim, broadly, a protecting-casing having an escape-pipe and safety-valve and a burner supplied with gas from the interior of said casing, such features being set forth in Letters Patent of the United States No. 301,191, granted and issued to me under date

10 of July 1, 1884.

I claim herein as my invention—

1. The combination of a railroad-track, a gas-main surrounded by a tight inclosing-casing for a portion of its length adjacent to said track, a pipe admitting gas at low pressure from the main to the interior of the casing, a lantern supported in position to be in view from the line of track, and a burner inclosed in said lantern and supplied with gas by a pipe from the casing, substantially as set forth.

2. The combination of a railroad-track, a gas-main surrounded by a tight inclosing-casing for a portion of its length adjacent to said track, a pipe admitting gas at low pressure from the main to the interior of the casing, a 25 lantern supported in position to be in view from the line of track, a burner inclosed in said lantern and supplied with gas by a pipe from the casing, and an escape-pipe leading out of the casing and fitted with a relief-valve 30 adapted to permit the escape of gas therefrom at a point beyond the access of fire projected from engines passing over the railroad-track, substantially as set forth.

In testimony whereof I have hereunto set my 35 hand.

GEO. WESTINGHOUSE, JR.
